RIBBON SHIFT MECHANISM FOR TABULATING MACHINES

Robert Duncan, Washington, D. C., and Lester F. Wilkinson, Garrett Park, Md., assignors to Government of the United States, represented by the Secretary of Commerce

Original application November 12, 1935, Serial No. 49,370. Divided and this application March 25, 1936, Serial No. 70,718

4 Claims. (Cl. 197—161)

(Granted under the act of March 3, 1883, as amended April 30, 1928; 370 O. G. 757)

The invention described herein may be manufactured and used by or for the Government of the United States for governmental purposes without the payment to us of any royalty thereon.

5 This invention relates to improvements in ribbon shift mechanisms, and more particularly to such a mechanism for use in connection with tabulating machines, although it may be utilized in other associations.

10 The printing mechanism to which this mechanism is especially applicable is shown and described in copending application Serial Number 49,370, filed November 12, 1935, for improvements in Tabulating machines, out of which the mechanism about to be described is divided, and is therefore to be considered as a division of said application.

15 The object of the invention is to provide a reliable, simple and durable mechanism for feeding the ribbon certainly in one direction as far as it should go, and then automatically reversing it, the reversal of movement being effected by building up of the ribbon upon one or the other of the spools to a point or to a degree at which 20 the built up ribbon operates upon a shifting device to reverse the ribbon, the power for actuating the mechanism being derived from any suitable source in the tabulating machine "tapped" at the moment of printing of the record and the 25 resetting of the numeral wheels of the tabulating machine.

In the drawings illustrating the invention—

Figure 1 is a front elevation of the shift mechanism mounted upon a support that is a part 30 of the tabulating machine frame.

Figure 2 is a top plan view of Figure 1.

Figure 3 is a top plan view and edge view of the upper pivoted shift plate shown in Figure 2.

Figure 4 is a similar view of the bottom pivoted 40 plate of Figure 2.

Figure 5 is a transverse section taken on the line 5—5, Figure 1.

Figure 6 is a side elevation of the mechanism for operating the shifting mechanism proper, 45 and

Fig. 7 is a detail side view and partial section of a cam and clutch mechanism utilized to motivate the shift mechanism, looking in the direction of the arrows.

50 Referring to the drawings, and first to Figure 6, A designates a part of the base of a tabulating machine frame, and B a downwardly-extending flange, the like of which is on the other side of the machine. Depending from the base is a hanger C, another hanger like it being also at-

tached to the base and properly spaced from the first, both hangers being utilized to support a transverse normally non-rotating shaft 1 that may be extended to have additional bearings in the flanges B. Upon this shaft, fast to it, is an eccentric 2 surrounded by an eccentric strap 3 that has formed integrally therewith an arm 4. A dog 5 is pivoted to the arm which has a shoulder 6 above its pivot and a tooth 7 below, the tooth being arranged to enter one or another of the notches 8 in the clutch disk 9 loose on the shaft, the shoulder of the dog being adapted to be engaged by the catch 10 on the lower end of a lever 11 pivoted at 12 to a side plate of the frame, and having a button 11' at one end. A 10 spring 13 seated in a recess in the base A tends to keep the catch 10 normally in the path of movement of the shoulder portion of the dog for a purpose that will presently appear. Fast to the clutch disk is a sprocket 13' which constantly 20 rotates so that rotary motion will be communicated to the shaft whenever the clutch disk and eccentric strap 3 are locked together, which occurs with each operation of the printing mechanism and when the ribbon mechanism is shifted. 25

The letter D designates a housing comprised in the main of two side plates D', one of which on the right-hand side of the machine is shown, the plate having forwardly-extending ears E, by which the housing is hung or pivoted to the shaft 1, so it may be rocked toward and from the main frame, and latched thereto for the printing operation, and swung away to inspect the results of such operation, and for other purposes. The plates D of the housing are braced by cross pieces 30 F and G, the upper brace F serving an important purpose in connection with the ribbon shift mechanism.

Journalized in the side plates D of the housing is a shaft 14 upon which is mounted an eccentric 40 15, which rides in a slightly elongated slot 16 in a rearward extension 17 of a vertically operating arm 18, whose upper end is provided with a shoulder head 19, the shoulder being arranged to engage the teeth of a ratchet 20 on the platen or 45 paper roll 21. The lower end of the vertical arm is slotted as indicated at 22 for the passage of a headed stud 23, the slot and stud connection serving to keep the arm in place and to aid in guiding it in its vertical movement assisted by its 50 engagement with the sides of a narrow slightly elongated recess 24 in the cross piece G—all clearly shown in Figure 6.

The shaft 14 carries a sprocket 25 fast thereto, and a similar sprocket 26 is carried by the 55

normally non-rotating shaft 1, the two being connected by a sprocket chain 27, shown in dotted lines only in Figure 6, the sprockets being alike so that the shafts 1 and 14 will be revolved 5 at the same rate when a revolution of shaft 1 takes place. The power for constantly driving the sprocket 13 by which the shaft 1 is driven may be from any suitable source.

10 *Ribbon shift*

The numerals 28 and 29 designate, respectively, two ribbon spools rotatably mounted in the brackets 30 on the edge of cross piece G, the shaft 31 of each spool carrying at its lower end a 15 beveled gear 32 always in mesh with similar gears 33 on the outer ends of short sleeves 34 rotatably supported in vertical brackets 35 also secured to cross piece G. Passing through these sleeves is a rotatable shaft 36 supported at its 20 opposite ends in hangers 37 on the under side of the cross piece. The shaft 36 carries a ratchet wheel 36' engaged by a spring urged pawl 37' pivoted to the arm 18, there being a spring 37" for preventing backward movement of the 25 ratchet. Each sleeve 34 carries a toothed clutch member 38 arranged to be engaged by similar clutch members 39 on the opposite ends of the long sleeve 40 which is slidably and rotatably mounted in hangers 41 secured to G. The shaft 30 36 extends through both of the sleeves 34 and also the sleeve 40, and while the short sleeves 34 are rotatable independently of the shaft 36, the sleeve 40 and said shaft must always rotate together, the means for assuring this joint motion being in the way of a pin 42 extending transversely through the shaft 36 with its ends protruding slightly through elongated slots 43 oppositely disposed in the sleeve 40, as shown in 35 Figures 1 and 5. Mounted centrally on the sleeve 40 and fast thereto is a disk 44 having an annular groove 45 therein for the reception of a shift pin 46 extending from the under side of a vertical tab 47 integral with the under side of a rectangular shift plate 48. This plate is pivotally mounted on a rigid extension 49 extending forwardly from the cross piece G, and forms a base for this plate 48, as well as another or upper plate 49' that rests upon the plate 48. The extension 49 carries a centrally located stud 50 40 near its front edge which is a pivot for the lower plate 48, and this pivot is extended considerably above said plate to serve additional purposes, as will appear. The lower plate is provided at each upper edge with a tooth or spur 51 for engagement with shoulders 52 of a stop block 53 mounted on the cross piece G, there being also in the plate 48 two notches 54 arranged to receive a spring-back ball 55 protruding slightly from a socket in the block, the purpose of the ball and notches being to stabilize the plate 48 in either of its rocked positions. The plate 48 is further provided with an arcuate slot 56 for clearance of the pivot of the upper plate.

65 A pin 57 on the plate 48 extends upwardly to be engaged by one or the other of the spurs 58 of the top plate 49' pivoted upon a stud 60 carried by the extension 49, and it is for the clearance of the stud that the slot 56 is provided in the plate 48, since the stud is stationary and the plate must rock or shift at certain times.

70 The upper plate 49' has a curved slot 61 which permits the rocking or shifting of plate 49' on its pivot, and the ends of the slot serve as stops to limit the throw of the plate 49' in either direction. This plate is further provided with a

stud 62 to which is pivoted a link 63, and attached to this link and to the stud 50 is a spring 64 that is gradually expanded as the ribbon builds up on a spool by a connection which will now be described, so as to be in readiness to "snap" 5 the top plate either to the right or left when the time comes to definitely operate the ribbon shift. The top plate 49' is provided with a stud 65 that passes through the arcuate slot 66 in the link 63, which stud extends also through a 10 roomy circular opening 67 in the center of the shift bar 68 whose opposite ends are pivoted adjustably at 69 in the bifurcated ends of levers 70 pivoted to the cross piece G as indicated at 71. Between ears 72 of the levers (best shown in 15 Figure 2) are rollers 73 that bear upon whatever ribbon is on the spools.

Operation

After each operation of the printing mechanism, which occurs after each run of cards, the tabulating mechanism to which this ribbon shift is shown applied, it is desirable to take a "print." At such time the button 11' (Figure 6) is pressed, rocking the lever 11, raising the catch 10, releasing the dog 5, causing its leaf spring 5' to rock the dog so that its tooth will enter a notch 8 in the clutch disk 9 locking the continuously rotating disk to the eccentric which is fast on the shaft 1, thus bringing about a single revolution of said shaft, which brings the dog that has traveled with the shaft back to its normal position, or that shown in Figure 6, when the catch 10 will again engage the shoulder of the dog and disengage its tooth from the notch, stopping 35 the rotation of all the parts. During this rotation of shaft 1, the shaft 14 is rotated once, the cam 15 raising and lowering the arm 18, causing the pawl 37' to rotate the ratchet the distance of one tooth, thus rotating the shaft 36 a short 40 distance, which rotates one or the other of the spools accordingly as to which of the clutch members is in engagement with a clutch member on short sleeve 34. As shown in Figures 1 and 2, the ribbon has been built up on the left-hand spool and the sleeve 40 has been shifted longitudinally of the shaft 36 to give the rotation of the right-hand spool 29. The slow step-by-step rotation of the spool gradually winds the ribbon from the spool 28 on to 29. As the 50 ribbon builds up it works the shift bar 68 toward the left, the bar meanwhile through its loose central connection with the stud 65 of the top plate 49', slowly rocks said plate on its pivot 60 until the pin 62 passes the center, when the 55 spring 64 will suddenly "snap" the plate the rest of the way, and in so doing a spur 58 will strike the pin 57 on plate 58, rocking said plate on its pivot 50, thus bringing a spur 51 against a shoulder 52 of the stop block to limit the movement 60 of the parts. Such a movement obviously shifts the other notch 54 to a position to be entered by the stabilizing ball 55. The shift is automatic, since the movement takes place only at each printing operation in step-by-step order at far- 65 apart intervals.

We claim:

1. In a ribbon shift mechanism, in combination, a pair of ribbon spools, a ribbon on said spools, a rotatable shaft, a rotatable member for 70 each spool having constant operative engagement with the spools, a shiftable member on the shaft and rotatable therewith and arranged to engage one spool rotating member at a time, a shift bar between the spools and formed with ends in con- 75

- tact with the ribbon on the spools, whereby as the ribbon is built up on one spool the shift bar will be gradually shifted, and means operated when the shift bar has passed a predetermined point to accelerate the movement thereof, and means operating at the time of such acceleration to shift the shiftable member to reverse a spool.
2. The mechanism as claimed in claim 1 characterized in that the means operated by the shift bar comprises two plates capable of independent movement, one plate being provided with means engaged by the shift bar and also means for moving the other plate, such other plate having an extension engaging the shiftable member on the shaft, and a spring operating on the shift bar engaging plate to accelerate the movement of said plate when it is past center, to rock the other plate to cause it to shift the shiftable member on the shaft.
3. In a ribbon shift mechanism, in combination, a pair of ribbon spools, a ribbon thereon, a rotatable shaft, a shiftable clutch means carried by the shaft for revolving the spools, a pair of independently pivoted plates, a shift bar in constant engagement with the ribbon on the spools and arranged to be shifted by the built up ribbon thereon, operative connections between the shift

bar and the plates, a spring operating upon one of the plates to accelerate its movement when said plate passes its pivotal center, means carried by one plate and arranged to engage means carried by the other to operate said other plate, and connections between said other plate and the clutch means, whereby said means is shifted.

4. In a ribbon shift mechanism, in combination, a pair of ribbon spools, a ribbon on said spools, a rotatable shaft, a rotatable member for each spool having constant operative engagement with each spool, a shiftable member on the shaft and rotating therewith, and arranged to engage one spool-rotating member at a time, a shift bar spanning the distance between the spools, a pair of pivoted links having their free ends pivotally connected with the ends of the shift bar, said links being provided with members in constant engagement with the ribbon on the spools, whereby as the ribbon is built up upon one spool the bar will be gradually shifted, and means operated when the shift bar has passed a predetermined point to accelerate the movement thereof, and means operating at the time of such acceleration to shift the shift bar to reverse a spool.

ROBERT DUNCAN.
